UNITED STATES PATENT OFFICE.

CLARENCE L. FETTY AND ALFRED A. HOSLER, OF AKRON, OHIO.

AUTOMATIC VACUUM AND GRAVITY FEED.

Application filed August 24, 1923. Serial No. 659,185.

To all whom it may concern:

Be it known that we, CLARENCE L. FETTY and ALFRED A. HOSLER, citizens of the United States, residing at Akron, in the county of 5 Summit and State of Ohio, have invented a new and useful Automatic Vacuum and Gravity Feed, of which the following is a specification.

This invention relates to valves for admitting and controlling the auxiliary air supply for internal combustion engines.

The object of the invention is to provide a simple and efficient device of this character which may be readily applied to an 15 intake manifold of an internal combustion engine and which will automatically function under varying operating conditions of the engine to admit the necessary amount of air or to cut off such air supply as requirements may demand and which takes care of 20 all surplus gases that are not properly mixed.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed without departing from the spirit of the invention.

In the accompanying drawings:—

35 Figure 1 represents a longitudinal section of the valve constituting this invention with the parts shown in the position assumed when the engine is idling or running up to 350 revolutions per minute.

40 Fig. 2 is a similar view with the parts in the position assumed when the engine is running ten miles per hour or less.

45 Fig. 3 is a similar view showing the position the parts assume when the speed is over ten miles per hour.

Fig. 4 is a transverse section taken on the line 4—4 of Fig. 2; and

Fig. 5 is a similar view taken on the line 5—5 of Fig. 3.

50 In the embodiment illustrated the device constituting this invention comprises a piston 1 having a stem 2 to be threaded into the intake manifold M of an internal combustion engine and which is secured in position by a lock nut 3. The piston 1 and

stem 2 have a bore 4 extending longitudinally therethrough from end to end thereof and communicating respectively with the manifold M and with the interior of a cylinder 20 which reciprocates on the piston 1 as will be hereinafter more fully described.

A compression spring 6 is located within the cylinder 20 between the outer end of the piston and a cap 7 swiveled on the inner end of an adjusting screw 8 which has threaded engagement with the outer end of the cylinder and which is held in adjusted position by a lock nut 9. A boss 5 is shown formed on the outer end of piston 1 around which the inner end of spring 6 is coiled and which holds the spring against lateral movement.

The piston 1 is provided in its perimeter at a point spaced inwardly from its outer end with an annular groove 10 which is one-sixteenth of an inch deep and from which lead to the bore 4 four radially disposed conduits 11 arranged in planes at right angles to each other, connecting said groove with the bore for a purpose presently to be described.

Spaced inwardly from groove 10 a suitable distance is a similar groove 12 which is three-thirty-seconds of an inch deep with eight conduits 13 connecting it with the bore 4. The conduits 13 are one-sixteenth of an inch in diameter and radiate from bore 4 as shown in Fig. 5 being spaced equal distances apart the purpose of which will be presently described.

The piston 1 is also provided with piston ring grooves 14 and 15 one being located between grooves 10 and 12 and the other at the rear of groove 12 and which are designed to form a fluid tight connection between the piston and the cylinder.

The cylinder 20 is provided about midway its ends with diametrically opposite apertures 21 and 22 which are one-sixteenth of an inch in diameter and are designed to admit air to the cylinder when the engine is idling or running up to 350 revolutions per minute. The apertures 21 and 22 connect the chamber 16 in the cylinder 20 with the atmosphere when the parts are in the position shown in Fig. 1 and when the engine is started the suction thereof will draw air in through the bore 4 and these openings and produce in the chamber a vacuum which in connection with spring 6 will op-

erate to draw the cylinder 20 inward over the piston 1 against the tension of spring 6 until the apertures 21 and 22 register with the groove 10 as shown in Fig. 2. When this occurs the conduits 11, four of which are provided, will permit sufficient air to enter the engine to produce a proper mixture when the engine is running up to ten miles per hour. The tension spring 6 is then 10 adjusted by means of the screw 8 and nut 9 and held in this position so that air will be drawn through openings 21 and 22 into groove 10 and thence pass through conduits 11 and bore 4 to the manifold producing a 15 proper mixture until a ten mile speed is exceeded. When the engine runs faster than ten miles per hour the vacuum in chamber 16 is lost and the cylinder 20 is released and moves outward until the opening 23 therein registers with the groove 12. This opening 23 is five-thirty-seconds of an 20 inch in diameter and when registering with groove 12 is designed to admit sufficient air to the cylinder through the eight conduits 13 to produce a proper mixture when the 25 motor is running faster than ten miles per hour.

A stop or safety screw 24 extends laterally through the inner end of cylinder 20 in the path of the inner end of the piston 1 and operates to limit the outward movement of the cylinder and to prevent its accidental detachment from the piston.

When the engine is running ten miles or 30 more the parts will remain in the position shown in Fig. 3 and will take care of all surplus gases that are not properly mixed.

We claim:—

1. An auxiliary air intake and regulating valve for internal combustion engines comprising a piston enclosed within a cylinder, said piston having a bore extending longitudinally therethrough and provided with a peripheral groove and having conduits connecting said groove and bore, said cylinder having an aperture to register at predetermined intervals with said groove and at other intervals with the interior of the cylinder above the piston, and means controlled by the suction in the engine in connection with which the device is used

for regulating the position of said aperture whereby more or less air is admitted through said bore.

2. An auxiliary air intake and regulating valve for internal combustion engines comprising a piston having a bore extending longitudinally therethrough and adapted to be secured to an intake manifold, said piston having a plurality of longitudinally spaced peripheral grooves with radial conduits connecting them with said bore, one groove having more conduits than the other, a cylinder encasing said piston and reciprocable thereon, said cylinder having a plurality of apertures arranged at longitudinally spaced intervals to register alternately with said grooves for supplying greater or less quantity of air to the manifold, and an adjustable spring located between said cylinder and piston for holding them in relative position, the suction of the engine controlling the amount of air supplied to the piston.

3. An auxiliary air intake and regulating valve for internal combustion engines comprising a piston having a bore extending longitudinally therethrough and adapted to be secured to an intake manifold, said piston having a plurality of longitudinally spaced peripheral grooves with radial conduits connecting them with said bore, one groove having more conduits than the other, a cylinder encasing said piston and reciprocable thereon, said cylinder having a plurality of apertures arranged at longitudinally spaced intervals to register alternately with said grooves for supplying greater or less quantity of air to the manifold, and an adjustable spring located between said cylinder and piston for holding them in relative position, the suction of the engine controlling the amount of air supplied to the piston, and means for limiting the movement of said cylinder relatively to the piston to prevent its accidental detachment.

In testimony that we claim the foregoing as our own, we have hereto affixed our signatures.

CLARENCE L. FETTY.
ALFRED A. HOSLER.
